UNITED STATES PATENT OFFICE.

THOMAS WILLIAMS, OF CALE, ARKANSAS.

NECK-YOKE.

1,282,157.

Specification of Letters Patent. Patented Oct. 22, 1918.

Application filed March 2, 1918. Serial No. 220,005.

To all whom it may concern:

Be it known that I, THOMAS WILLIAMS, a citizen of the United States, residing at Cale, in the county of Nevada and State of 5 Arkansas, have invented certain new and useful Improvements in Neck-Yokes, of which the following is a specification.

The primary object of this invention is to materially lessen the work on a team of 10 horses harnessed to a vehicle in the usual manner through the intervention of a pole or tongue and a neck yoke.

In the usual way of hitching a team of horses to a vehicle having a pole or tongue, 15 a neck yoke is employed and has connection with the tip of the pole or tongue in a manner to provide relatively longitudinal movement of the neck yoke, hence the animals being coupled to each other and to the pole 20 or tongue by means of the neck yoke, are subjected to side thrust and jerks incident to the lateral play of the pole or tongue by the movement of the front axle when the vehicle is traveling over rough ground.

25 The purpose of this invention is to yieldably connect the neck yoke with the pole or tongue so that shock incident to side thrust is compensated for, thereby preventing the shock being transmitted to the animals which 30 is a source of discomfort, thereby adding materially to the work and causing the animals frequently to become fretted.

The invention consists of a yieldable connection between the pole ring and opposite 35 ends of the neck yoke whereby side thrust and jerk of the pole or tongue is neutralized.

The drawing illustrates a preferred embodiment of the invention, however, it is to be understood that in adapting the same to 40 meet different conditions, various changes in the form, proportion, and minor details of construction may be resorted to without departing from the nature of the invention as claimed hereinafter.

45 In the drawings:

Figure 1 is a view in elevation of a neck yoke embodying the invention.

Fig. 2 is a transverse section on the line 2—2 of Fig. 1 showing the parts on a larger 50 scale.

Corresponding and like parts are referred to in the following description and indicated in both views of the drawings by like reference characters.

55 The numeral 1 designates a neck yoke which may be of any construction commonly

employed for the hitching of a team of draft animals to a vehicle having a pole or tongue.

The numeral 2 designates the rings generally provided at the ends of the neck yoke 60 for receiving the straps, chains, or other connecting means between the collars or breast straps and the neck yoke. The ends of the neck yoke are provided with the usual metal tips 3 to which the rings 2 are connected in 65 a manner well understood.

A ring 4 is disposed centrally of the neck yoke and is designed to receive the tip or forward end of the pole or tongue of the vehicle. In accordance with the present invention, the ring 4 is yieldably connected to the neck yoke so as to neutralize shock and other like movement tending to produce a jerk or sudden endwise movement of the neck yoke, and which generally results in 75 fretting the animals and adding to their work. In accordance with the invention, two helical springs 5 and 6 are mounted upon opposite end portions of the neck yoke and are connected at their outer ends to the 80 extremities of the neck yoke in any desired way, the inner ends of such springs being loose and attached to the pole ring 4 in any manner. As indicated in Fig. 1, the springs 5 and 6 are of the open type, i. e., the convolutions are spaced apart, hence both springs act jointly in neutralizing the shock, one spring by expansion, and the other 85 spring by contraction and vice versa. The inner or opposing ends of the springs 5 and 90 6 are looped about the ring 4, hence the latter is free to move in the usual manner, and in addition has a relative movement lengthwise of the neck yoke against the combined tension of the two springs 5 and 6. 95

In practice, the neck yoke is positioned in the manner well understood, the forward end of the pole or tongue being engaged with the ring 4 and the collars or breast straps being connected to the rings 2. It will thus be 100 understood that lateral swaying of the pole or tongue at its forward end tends to move the ring 4 lengthwise of the neck yoke against the tension of the springs 5 and 6, and such springs neutralize the resultant 105 jerk, thereby relieving the animals of the annoyance commonly experienced which tends to fret and increase or add materially to the work.

What I claim is:

1. A neck yoke having helical springs mounted upon opposite end portions thereof

with their convolutions spaced apart, and a pole ring connecting the inner or opposing ends of the springs and attached to the neck yoke thereby, said spring serving to neutralize shock and having their outer ends attached to the extremities of the neck yoke.

2. A neck yoke provided at its ends with the usual rings for attachment therewith of the breast strap or collar connections, extensible helical springs mounted on opposite end portions of the neck yoke and having their outer ends connected to the ex-

tremities thereof and a pole ring having the inner or opposing ends of the springs attached thereto, said springs forming connecting means between the neck yoke and pole ring and in turn serving to unitedly compensate for and neutralize shock. 15

In testimony whereof I affix my signature in presence of two witnesses.

THOMAS WILLIAMS.
